UNITED STATES PATENT OFFICE

JOHN R. HOLMES, OF LOCKPORT, NEW YORK, ASSIGNOR TO HARRISON RADIATOR CORPORATION, OF LOCKPORT, NEW YORK, A CORPORATION OF NEW YORK

FOOT RAIL CAR HEATER

Application filed December 9, 1931. Serial No. 579,871.

This invention relates to heating devices for automotive vehicles and has particular reference to the type of heater which uses the hot water of the circulating system of the engine. In the invention, the heater is formed as a foot rest at the rear seat and is swingably mounted on pivots at its two ends as is customary for the foot rest. The hot water from the engine cooling system is delivered at one end of the heater and withdrawn at the other end, the heater comprising a honeycomb structure with numerous passages and a large radiating surface so that the hot water in passing from one end to the other will deliver its heat from the radiating surfaces to the air in the vehicle.

The particular heating unit of the invention comprises two honeycomb structures which are spaced from each other and enclosed in a metal protecting casing or cover.

On the drawings:

Figure 1 shows a sectional view through an automotive vehicle showing the heater applied.

Figure 2 is an enlarged detailed side view of the heater.

Figure 3 is a plan view of the heater with parts broken away and shown in section and taken substantially on the line 3-3 of Figure 2.

Figure 4 is a section on the line 4-4 of Figure 3.

Figure 5 is a section on the line 5-5 of Figure 3.

Figure 6 is a section on the line 6-6 of Figure 2.

Figure 7 is a section on the line 7-7 of Figure 6.

Referring to the drawings, the numeral 2 indicates an automotive vehicle as a whole. The vehicle has the engine 4 with the usual water circulating system 6 including a water pump 8. The dashboard is indicated at 10, the cowl at 12, the instrument panel at 14, the toe board at 16, the floor board at 18, the front seat at 20, and rear seat at 22. These parts are conventional and per se form no part of the invention.

The heating unit of the invention is indicated as a whole at 24 and is positioned in the

rear compartment of the vehicle between the front seat 20 and the rear seat 22. The heating unit takes the hot water of the engine circulating system from a pipe 26 and delivers it to one end of the heater and returns it through a pipe 28 from the other end of the heater to the cooling system of the engine. A valve 30, controlled by a link 32 and a button 34 at the instrument panel, is adapted to disconnect or connect the water through the heater.

The pipes 26 and 28 have suitable water tight connections 36 at their ends which are attached to connecting members 38 which extend through the floor board 18. The connections are screwthreaded, as indicated at 40, and have the nut 42 and washer 44 below the floor board and the internally threaded elbow 46 above the floor board. By tightening the elements 42 and 46, a rigid and water tight connection is obtained. Each elbow 46 has the dome portion 48 in which there is formed a seat 50 which receives the flow member 52. The flow member has the openings 54 at opposite sides to allow the water to pass from the elbow 46 to the interior of the flow member. The flow member 52 has a tight fit in the seat 50 and is tapered, as shown in Figure 6. A gasket 56 and a nut 58 tightly hold the flow member on its seat and form a water tight connection at one end. The flow member 52 and seat 50 have a relatively large bearing surface at the opposite side at 60 which forms a water tight connection.

Each flow connection 52 terminates in an elbow 62 which has a water tight connection 64 with an inlet pipe 66 at one side of the heater and with an outlet 68 at the other side of the heater. The inlet pipe 66 has a plurality of openings 70 at one side thereof to allow the water to flow into an inlet jacket 72 at the end of the heater. The end of the inlet pipe 66 is closed by means of a plug 74 in water tight relation. The jacket 72 surrounds the inlet pipe, as shown at 76, and is secured thereto in water tight relation. The outlet pipe 68 is similarly constructed and has the openings 70 at one side, a similar plug 74 and an outlet jacket 78. The outlet jacket is secured around the outlet pipe 68

as indicated at 76. The inlet jacket 72 and outlet jacket 78 are secured in water tight relation to a honeycomb structure indicated as a whole at 80 and which extends the length of 5 the heater 24 between the inlet and outlet passages. The honeycomb structure comprises the upper and lower sections 82 and 84 which are spaced apart by any suitable means. The honeycomb structure is reticulated in form 10 and causes the water to pass from one end to the other in a zigzag passage so as to give a slow movement of water therethrough. The zigzag passage and honeycomb structure also affords a large radiating surface so 15 that when the hot water passes through the heater, the air surrounding it will absorb the heat and heat the interior of the vehicle.

The honeycomb structure and inlet and outlet pipes are surrounded by a protecting 20 jacket or cover 88. The jacket comprises the telescopic upper and lower parts 90 and 92, the two being secured together by means of the bolts and nuts 94. Bolts 96 are tapped into the plugs 74 at the inlet and outlet pipes 25 and rigidly clamp the casing 88 to the inlet and outlet pipes to form a rigid structure. At the front portion where the inlet and outlet pipes emerge from the casing, the members 90 and 92 are slotted to accomodate the 30 pipes. At its upper and lower portions where it extends over the honeycomb structure, the casing members 90 and 92 are ribbed or formed trellis like, as shown at 98 and 100, to allow for a radiation for the heat from the 35 heating unit. The parts 98 are flat and join the ribs 101.

The protecting jacket or casing 88 acts as a shield for the heater element and prevents 40 damage thereto, thereby preventing leaks in the water circulating system.

The jacket or casing also takes the strain or foot pressure and transmits none to the heating element thereby preventing damage to the heating element.

45 I claim:

1. In a heater for an automotive vehicle, a water inlet at one end of the heater, a water outlet at the other end, an upper and a lower honeycomb structure between said 50 inlet and outlet through which the water flows, and a protecting casing surrounding said inlet and outlet and honeycomb structure.

2. In a means for heating an automotive vehicle having a floor, a heater secured to and positioned above the floor, a water inlet at one end of the heater, a water outlet at the other end, an upper and a lower honeycomb structure between said inlet and outlet 55 through which the water flows, and a two-part interfitting protecting casing over said inlet and outlet and honeycomb structure.

3. In a means for heating an automotive vehicle having a floor, a heater secured to and 60 positioned above the floor, a water inlet at one

end of the heater, a water outlet at the other end, an upper and a lower spaced honeycomb structure between said inlet and outlet through which the water flows, and a protecting casing surrounding said inlet and outlet and honeycomb structure.

4. In a heater for an automotive vehicle, a water inlet at one end of the heater, a water outlet at the other end, means passing through the floor of the vehicle and delivering water to the inlet and passing water from the outlet, a journalled connection between said means and the inlet and outlet permitting the heater to swing from a position to be used as a foot rest to a position adjacent the vehicle seat, an upper and lower spaced honeycomb structure between the inlet and outlet and through which the water flows, and a protecting casing surrounding said honeycomb structure.

In testimony whereof I affix my signature.

JOHN R. HOLMES.
